SOLOMON MALLIN, OF PITTSBURGH, PENNSYLVANIA.

STEM WINDING AND SETTING DEVICE FOR WATCHES.

1,189,713.

Specification of Letters Patent.

Patented July 4, 1916.

Application filed March 8, 1916. Serial No. 82,801.

To all whom it may concern:

Be it known that I, SOLOMON MALLIN, a subject of the Czar of Russia, residing at Pittsburgh, in the county of Allegheny and 5 State of Pennsylvania, have invented certain new and useful Improvements in Stem Winding and Setting Devices for Watches, of which the following is a specification.

This invention relates to stem winding 10 and setting devices for watches, particularly adapted for use in connection with the cheap grade of watch now sold at small expense, although the device is adapted to any form of watch wherein it is found applicable, and 15 the invention has for its primary object to provide a device of such class, with means in a manner as hereinafter set forth, to overcome the necessity of shifting the stem in and holding it in when winding the watch 20 as is the practice now in general vogue in connection with the popular price watches now on the market.

Further objects of the invention are to provide a stem winding and setting device 25 for watches, capable of being attached to the cheap grade of watch now in general use without changing or rearranging any of the parts of the watch mechanism under such conditions providing for the employment of 30 the device in accordance with this invention without increasing to any material extent the expense of manufacturing the cheap grade of watch now in general use.

Further objects of the invention are to 35 provide a stem winding and setting device for watches which is simple in its construction and arrangement, strong, durable, efficient and convenient in its use, and inexpensive.

With the foregoing and other objects in view the invention consists of the novel construction, combination and arrangement 40 of parts as hereinafter more specifically described and illustrated in the accompanying drawings, wherein is shown an embodiment 45 of the invention, but it is to be understood that changes, variations and modifications can be resorted to which come within the scope of the claims hereunto appended.

In the drawings wherein like reference characters denote corresponding parts throughout the several views:—Figure 1 is a rear elevation of a watch mechanism, broken away, showing the adaptation therewith of 50 certain of the elements of the stem winding and setting device in accordance with this

invention. Fig. 2 is a rear elevation of a portion of the watch mechanism showing the adaptation therewith of the winding pinion and setting gear of a stem winding and setting device in accordance with this invention. 60 Fig. 3 is an enlarged sectional view illustrating the setting gear and winding pinion of a stem winding and setting device in accordance with this invention. Fig. 4 is a 65 top plan view illustrating the setting gear of the device showing the adaptation therewith in connection with one of the gears of a chain of gears for setting the hands. Fig. 5 is a rear elevation illustrating the stem in 70 an inward position. Fig. 6 is a like elevation illustrating the stem in an outward position.

Referring to the drawings in detail 1 denotes a pillar plate of a watch mechanism having connected therewith the setting gears 75 2, 3, for the hands.

4 denotes a pillar plate of the watch mechanism which opposes the plate 1, the latter as well as the plate 4 has the marginal portion thereof cut away as at 5.

Secured between the plates 1, 4, is an outer supporting member 6 and an inner supporting member 7 which are spaced from each other and the former is positioned to extend across the openings 8 formed by the cut away 85 portions 5. The member 7 is arranged inwardly with respect to the cut away portion 5 and the said members 6, 7, are secured, as at 9, to the plates 1, 4.

The member 6 has an opening 10 through 90 which extends a rotatable barrel 11 having a squared bore 12. The outer end of the barrel 12 is flanged as at 13 and overlaps the outer face of the member 6. The inner end of the barrel 11 has formed integral therewith a setting gear 14 which meshes with the gear 2 of the chain of gearing for setting the hands. The barrel 11 continuously rotates as is obvious, that is to say when the watch 95 is going.

The member 7 is provided with an opening 15 through which extends a barrel 16, the latter consisting of an inner and an outer section, and the inner end of the outer section is toothed and engages with the toothed outer end of the inner section. The sections are maintained together by a spring 20 which bears against said inner section, the latter is indicated at 21. The barrel 16 is provided with a pinion 18, the latter being upon the outer section of the barrel and said pinion 18 is arranged inwardly with respect to the 100 105 110

member 7 and is adapted to engage with the gearing for winding the power transmitting spring of the watch mechanism. The barrel 16 has the outer section thereof flanged, as 5 at 19, and the said flange engages the outer face of the member 7 and in connection with the pinion 18 couples said outer section of the barrel 16 with the member 7. The barrel 16 is provided with a square pocket 17 10 and the latter is arranged in the inner section of the barrel 16.

The reference character 22 denotes a stem, having a squared head 23, and a reduced cylindrical portion 24, which carries a boss 15 25 to arrest outward movement of the stem. The stem above the boss 25 is enlarged and grooved as at 26 to receive a pair of holding springs 27. A cap 28 is connected to the outer end of the stem and the latter is 20 surrounded by a sleeve 29, to which is connected a ring or swivel 30. The cap 28 can shift inwardly or outwardly on the outer end of the sleeve. The normal position of the stem is such that the head 23 will seat 25 in the pocket 17 then by turning the head the squared head 23 will rotate the barrel 16 and pinion 18 and under such conditions winding the power transmission springs of the watch mechanism. The diameter of the 30 reduced portion 24 of the stem 22 is such that it will not engage the wall of the squared bore 12 of the barrel 11, under such conditions the rotation of said barrel will not be retarded. If it be desired to set the 35 hands the stem is pulled outward until the head 23 engages the squared bore 12 of the barrel 11 and then by rotating the cap, the head 23 will revolve the barrel 11, causing the setting gear 19 to be carried therewith 40 and imparting rotation to the gears 2, 3, to set the hands.

By setting up the barrel 16 in two sections the stem can be revolved backwardly without revolving the outer section of the barrel 45 which carries the pinion 18. When the stem is moved forwardly to revolve the pinion 18 the teeth of the inner section of the barrel 16 will engage in the teeth of the outer section and carry the latter therewith. 50 When the stem is revolved backward the teeth of the section 21 will ride over the teeth of the outer section of the barrel.

What I claim is:—

1. A stem winding and setting device comprising a pair of spaced members adapted to be arranged between the pillar plates of a watch mechanism, a setting gear rotatably supported by one of said members and adapted to be permanently in engagement 55 with the chain of gears for setting the hands, a normally stationary winding pinion rotatably suspended from the other of said members and engaging with the winding elements of a watch mechanism, and a shiftable stem having means normally engaging

with said winding pinion for rotating the latter when the stem is rotated, said means when said stem is shifted outward capable of engaging with said setting pinion for actuating it to operate the setting mechanism for the hands. 70

2. A stem winding and setting device comprising a pair of spaced members adapted to be positioned between a pair of pillar plates of a watch mechanism, a barrel rotatably supported by one of said members, having a squared bore and further having a setting pinion at its inner end engaging with the hand setting device of a watch mechanism, a barrel carried by the other 75 of said members and provided with a winding pinion and further provided with a square pocket, and a shiftable stem capable of engaging in said pocket for actuating said winding pinion to operate the watch 80 mechanism, and further capable of engaging in said squared bore to actuate the hand setting means of a watch mechanism. 85

3. In a stem winding and setting device for watches the combination with a pair of 90 pillar plates having the marginal portions cut away to provide a pair of opposed openings, a member secured between said plates and extending across said openings, a rotatable barrel supported by said member and 95 having a squared bore and further having its inner end provided with a setting gear, said openings providing clearance for said setting gear, a member secured between said plates inward with respect to said gear, a 100 barrel supported by said second member and carrying a winding pinion and further having a square pocket and a shiftable stem having a reduced inner end terminating in a square head capable when the stem is 105 shifted inwardly to engage in said pocket to rotate said pinion and when shifted outward to engage in said bore to rotate said setting gear.

4. A stem winding and setting device comprising a barrel adapted to be rotatably supported between the pillar plates of a watch mechanism and provided with a squared bore and further having a setting gear, a 110 barrel adapted to be rotatably supported between said plates inwardly with respect to said gear and provided with a winding pinion and further provided with a square pocket, and a shiftable stem having its inner 115 end provided with a head capable when the stem is shifted inwardly to engage in said pocket and rotate said pinion and when shifted outwardly to engage in said square bore to rotate said gear.

5. A stem winding and setting device 120 comprising a barrel adapted to be rotatably supported between the pillar plates of a watch mechanism and provided with a squared bore and further having a setting gear, a barrel adapted to be rotatably sup- 125

ported between said plates inwardly with respect to said gear and provided with a winding pinion and further provided with a square pocket, and a shiftable stem having its inner end provided with a head capable when the stem is shifted inwardly to engage in said pocket and rotate said pinion and when shifted outwardly to engage in said square bore to rotate said gear, said stem

having a reduced portion to prevent engagement with the inner faces of said barrels.

In testimony whereof I affix my signature in the presence of two witnesses.

SOLOMON MALLIN.
